UNITED STATES PATENT OFFICE.

FREDERICK BUCHHORN, OF CHICAGO, ILLINOIS.

WATER-FILTER.

SPECIFICATION forming part of Letters Patent No. 375,798, dated January 3, 1888.

Application filed August 25, 1887. Serial No. 247,875. (No model.)

To all whom it may concern:

Be it known that I, FREDERICK BUCHHORN, a citizen of the United States of America, residing at Chicago, in the county of Cook and State of Illinois, have invented certain new and useful Improvements in Water-Filters, of which the following is a specification, reference being had therein to the accompanying drawings.

10 This invention relates to filtering apparatus adapted to be coupled to any hydrant-faucet for filtering the water as it is used, and it has for its object to provide such an apparatus that will be self-cleaning of all impurities separated from the water while passing through it; and with that object in view my invention consists of the novel devices and combinations of devices, hereinafter described and specifically claimed.

20 In the accompanying drawings, Figure 1 represents a vertical section through the center of the apparatus; Fig. 2, an elevation of the inside tube and perforated diaphragm detached; and Fig. 3, a bottom view of the apparatus, the screw-nozzle being removed.

25 Corresponding letters designate like parts in the several figures of the drawings.

A denotes the cylindrical casing provided with caps B and C, screwed upon the ends 30 thereof. The cap B has a central screw-neck, b, for coupling it to the screw-threaded spout end of a common faucet, D, a rubber ring, a, being interposed between a shoulder inside of the screw-neck b and the end of the faucet- 35 spout for forming a hermetic joint. The bottom cap, C, is also provided with a central screw-neck, c, to which is coupled, by a collar-nut, d, a nozzle, E. Against an annular shoulder inside of screw-neck c is placed a rubber 40 ring, e, and against this rubber ring e is inserted a metal disk, F, being notched on its edges and bottom to provide small channels f. This disk F rests with its under edge upon the upper end of nozzle E, and has a stem, g, that 45 extends through rubber ring e upward into casing A. By tightening the coupling-nut d the disk F will be forced against rubber ring e, so as to form a hermetic joint therewith. By closing channels f no water can escape there- 50 through; but by loosening the nut d the passage of water through these channels f into nozzle E can be adjusted to be more or less.

A tube, G, is inserted into casing A, with its lower end resting upon rubber ring e. This tube G has secured a perforated diaphragm, H, the diameter of which is equal to the diameter of the bore of the casing, and which when the tube G is placed in position will be a short distance above cap C, resting with its downwardly-curved periphery upon such cap C. The tube G also has a collar, i, near its upper end, upon which is placed a washer-shaped perforated diaphragm, I, the diameter of which is also the same as the bore of casing A. This diaphragm I is held in position by 65 a conical rubber ring, J, placed over the upper end of tube G and resting with its lower end upon the diaphragm I and collar i, and bearing with its upper end against the under side of cap B, so as to form a hermetic 70 connection between screw-neck b and tube I. The lower end of tube I, below diaphragm H, is vertically slotted, or it may be perforated with holes for providing communication between the interior of tube I and the space between diaphragm H and cap C. A goose-neck pipe, K, being the escape-spout for the filtered water, is tapped into cap B.

The cylindrical space between tube G and casing A and between diaphragms H and I is 80 filled with gravel, sand, or charcoal, or with any other suitable filtering material.

The *modus operandi* of the apparatus is as follows, to wit: The coupling-nut d being sufficiently loosened, so as to allow a limited 85 escape of water through nozzle E, and the faucet D being turned open, the tube G will be filled with water, which, passing through the slits or perforations in the bottom end of said tube and entering the space below diaphragm 90 H, will rise through the filtering material, and will thence escape through pipe K. The impurities of the water will collect in the space below diaphragm H, and after shutting faucet D the water contained in the apparatus will 95 leak through channels f and nozzle E, washing with it all impurities separated with each draft of water through the filter. Thus the apparatus will be continuously self-cleaning.

The casing of this apparatus may be made 100 globular, instead of cylindrical, shape.

What I claim is—

1. In a filter of the kind described, the combination of a filtering-chamber having a screw-

threaded extension on, and a discharge-pipe, K, connected to, its upper end, a central open tube, G, having the perforated diaphragm H upon its lower end over the bottom of the filter chamber, and the perforated diaphragm 5 and rubber ring J, surrounding the top of the tube, said ring lying between the diaphragm I and top of the chamber, as set forth.

2. The combination of casing A, having the 10 screw-threaded necks b and c and the pipe K at the top thereof, the tube G, perforated at its bottom, the perforated diaphragms H and

I, set over the tube G at bottom and top, and a notched disk, F, packing-ring e, and nozzle E, secured to the neck on the lower end of 15 the casing, substantially in the manner and for the purpose set forth.

In testimony whereof I affix my signature in presence of two witnesses.

FRED. BUCHHORN.
